UNITED STATES PATENT OFFICE.

CHARLES F. BROWN, OF BRISTOL, RHODE ISLAND.

IMPROVEMENT IN MACHINES FOR ROLLING ROUND TAPERED BARS.

Specification forming part of Letters Patent No. 142,372, dated September 2, 1873; application filed July 26, 1873.

To all whom it may concern:

Be it known that I, CHARLES F. BROWN, of Bristol, in the county of Bristol and State of Rhode Island, have invented a new and useful Improvement in Machine for Rolling and Straightening Tapering Forms, of which the following is a specification:

My object in the present invention is to facilitate the manufacture of spindles for factories, axles for carriages, and all other articles of tapering form; and it consists of two eccentric or cam-faced disks revolving in opposite directions on a central arbor in a suitably-constructed frame, so beveled as to roll or straighten a tapering spindle or other article, and in one or more guides through which the article to be tapered is introduced, all as hereinafter more fully set forth and described.

In the accompanying drawing, Figure 1 represents a side view of the machine. Fig. 2 is a horizontal section of Fig. 1 taken on the line *xx*.

Similar letters of reference indicate corresponding parts.

A represents the bed-plate. B is the frame which rises from the bed-plate. C is a central arbor, supported at top and bottom by the bed-plate and the frame B. D is a disk attached to the upper part of the frame. E represents the horizontal driving-shaft, which revolves in the tubular box F, with a bevel-pinion, G, on its inner end. H and I are the main operating-disks, to which are attached the cog-wheels J J, which engage with the pinion G. The disk H and the bevel cog-wheels J may be cast in one piece. The faces of the disks H I are beveled from the center to the periphery, and are cam-shaped or eccentric from the offsets K K, and are revolved in opposite directions around the central arbor C by the revolution of the pinion G. L is a vertical guide attached to one or both sides

of the machine, in which is a central hole, M, through which the pieces of metal to be tapered are introduced. When the offsets K K are opposite this guide-hole the opening between the disks is greatest.

As the disks revolve in opposite directions the spindle or other piece of metal is revolved between them, and is given a tapering form at one revolution by reason of the beveled and eccentric surfaces of the disks. These disks are duplicates of each other, and revolve in unison. The eccentric surfaces have the effect of inclined planes upon the spindle, approaching each other in one part of their revolution, and receding from each other in another part, while the spindle simply revolves and receives its form and shape from the pressure imparted by the beveled and eccentric revolving surfaces.

This machine is used for straightening spindles and other articles as well as forming them, and performs its work, whether in forming or straightening tapering forms, in the most perfect and expeditious manner.

I do not confine myself to the precise form of the parts shown, as variations may be made in many ways without departing from my invention.

Having thus described my invention, I claim as new and desire to secure by Letters Patent—

A machine with two disks, having cam or eccentric faces revolving in opposite directions on a central arbor or spindle, and beveled in such manner as to roll or straighten a taper-spindle or other article, substantially in the manner described.

CHARLES F. BROWN.
